(57) **CLAIM**

The ornamental design for a pedestal computer docking station, as shown and described.

DESCRIPTION

FIG. 1 is a top and left side perspective view of a pedestal computer docking station showing my new design, the elements shown in broken lines are for illustrative purposes only and form no part of the claimed design;

FIG. 2 is a front view thereof;

FIG. 3 is a back view thereof;

FIG. 4 is a side view, an opposing side view being the mirror image thereof;

FIG. 5 is a top view thereof; and,

FIG. 6 is a bottom view thereof.
